UNITED STATES PATENT OFFICE.

LIONEL J. CHAPMAN, OF HANOVER, PENNSYLVANIA, ASSIGNOR TO THE LONG FURNITURE CO., OF HANOVER, PENNSYLVANIA, A CORPORATION OF PENNSYLVANIA.

EXTENSION-TABLE.

1,099,787.

Specification of Letters Patent.

Patented June 9, 1914.

Application filed April 10, 1908. Serial No. 426,372.

To all whom it may concern:

Be it known that I, LIONEL J. CHAPMAN, a citizen of the United States, residing at Hanover, in the county of York and State of Pennsylvania, have invented a new and useful Extension-Table, of which the following is a specification.

This invention relates more particularly to pedestal tables, though there are features 10 probably useful in connection with extension tables of other types.

The primary object of the present invention is to provide novel, simple and effective means whereby upon the movement of either 15 top end section, the other end section will be moved in an opposite direction so that the table will always be properly extended and contracted and the pedestal or other support will be properly centered with respect thereto, the structure moreover being 20 simple and readily applicable to the ordinary type of table without material alterations therein.

The preferred embodiment of the invention is illustrated in the accompanying drawings, wherein:

Figure 1 is a bottom plan view of the table top with the pedestal shown in section. Fig. 2 is a detail sectional view on the 30 line 2—2 of Fig. 1. Fig. 3 is a sectional view on the line 3—3 of Fig. 1. Fig. 4 is a detail cross sectional view on the line 4—4 of Fig. 1.

Similar reference numerals designate corresponding parts in all the figures of the drawings.

In the embodiment disclosed, a center or supporting member is employed comprising a pedestal 5 carrying on its upper end a 40 buck frame composed of crossed bars 6. Spaced parallel slides 7 are fixed to the ends of the crossed bars 6 by screws 7 or other suitable fasteners. The table top comprises separable end sections 8 having sets of slides 45 9 that are respectively and slidably engaged with opposite sides of the slides 7 in a manner well understood to those skilled in this art. So far as thus described, nothing is claimed for the table, the structure being 50 well known and being open to a serious objection, that is to say, either end section of the top may be drawn out independently of the other end. Consequently it often happens that if the top is extended, the pedestal 55 will be at one side of the center so that not

only is the symmetry of said table destroyed, but the top is improperly supported. Moreover it is very difficult for one person to open and close the table, and ordinarily two are required. In order to eliminate this objectionable feature, the following mechanism is preferably employed. It will be observed particularly by reference to Fig. 4 that the center or intermediate slide 7 of each set is wider than the outer slides, and 60 secured to the lower faces of said outer slides, are racks 10, the fasteners therefor being shown at 11. The teeth of these racks are oppositely disposed. The center slides 7 have the central portions of their under 65 sides cut away, as shown at 12, and journaled in said cut-away portions are gears 13, which are in mesh with the racks. The journals for said gears are screws or other headed fasteners 14, which also serve to hold the 70 gears in place. With this construction, it will be evident that if one of the end sections 8 of the top is drawn outwardly, the 75 slides thereof will be moved in a corresponding direction, and the racks carried by said 80 slides will therefore cause the rotation of the gears 13. These gears being in mesh with the racks on the slides of the opposite end sections, will effect the movements of said other slides in an opposite direction. 85 Therefore the other end section will be moved outwardly a corresponding distance. The result is that the pedestal will always be centered, the symmetry of the table will not be destroyed, and the table top can be 90 extended and contracted by one person. One of the principal features of this invention resides in the arrangement of the rack-bars along the underside of the slides 9 to which they are rigidly secured. As shown in Fig. 95 3, the rack bars are slightly narrower than the width of the slides to which they are fastened. Moreover, the gear wheels 13 are wider than the fixed slide rails 7, so that their teeth overlap the adjacent slides 9, the meshing of the teeth of the gear wheels and racks being to one side of the line of separation of the slides 7 and 9.

From the foregoing, it is thought that the 105 construction, operation and many advantages of the herein described invention will be apparent to those skilled in the art, without further description, and it will be understood that various changes in the size, shape, proportion, and minor details of construc- 110

tion, may be resorted to without departing from the spirit or sacrificing any of the advantages of the invention.

Having thus fully described my invention, 5 what I claim as new, and desire to secure by Letters Patent, is:—

1. In an extension table, the combination with the central vertical support, and a pair of fixed, spaced slide rails located one on either side of the support and carried thereby, of a table top comprising separable end sections, a pair of opposed slide rails beneath each end section, said sliding rails being attached thereto and projecting therefrom, the slide rails of the end sections slidably contacting at their sides with the fixed slide rails, gear wheels rotatable in a horizontal plane and mounted on each fixed slide rail section near the middle thereof, and 15 fixed racks on the bottom of each end slide rail and supported along their whole length thereby, and engaging with the said gear wheels on the fixed slide rails.
2. In an extension table, the combination 20 of a supporting base provided with spaced parallel fixed slide rails, a table top formed of separable sections, a pair of spaced rails

secured to one end section and slidably engaging the opposed inner faces of the slide rails, a pair of spaced rails secured to the other end section and slidably engaging the outer faces of the slide rails, a vertically-disposed, rigidly-mounted pivot on each fixed slide rail at approximately the center thereof, a pinion mounted on each pivot and having a diameter greater than the width of the fixed slide rails so as to extend beyond the opposite edges of the slide rails and overlap the rails of the table top sections, and rack bars arranged along and secured rigidly to the bottom of the rails of the table top sections and having a diameter less than the width of the said rails and meshing with the pinions for causing simultaneous movement of the table sections upon the movement of either table section. 40

In testimony, that I claim the foregoing as my own, I have hereto affixed my signature in the presence of two witnesses.

LIONEL J. CHAPMAN.
